HOISTING APPARATUS

Rudolph Payson, Flushing, N. Y.

Application January 20, 1939, Serial No. 251,899

11 Claims. (Cl. 254—187)

This invention relates to hoisting apparatus and while it is not limited to a specific use, I have shown the same embodied in the form of a hand and power winch of the type installed in hoistways of buildings and mounted upon a telescopic mast of the character covered by my Patent No. 2,018,568, October 22, 1935, so that the hoist may be raised from a storage position in an areaway to a working position above the areaway and then returned again to the storage position.

This type of hoisting apparatus is commonly used for raising ashes in cans from the basement of a building by a cable to the sidewalk level and for lowering the empty cans or other objects. As described in the above patent, an operator, wishing to remove ashes from an areaway, stands at the bottom of the areaway and operates the driving mechanism of the telescopic mast which elevates the winch thereon, opens the areaway doors and positions the winch at an operating level above the areaway. The winch is then operated to lower its cable. The present invention provides a control mechanism for the lowering of the cable with speed and safety. The movement of the cable usually presents a hazard to the operator handling the container at the bottom of the areaway.

It is an object of this invention to provide means normally to maintain the winch mechanism in a safety adjustment.

It is a further object of this invention to provide means to normally maintain the hoist mechanism in operative engagement and locked against descending operation.

It is a further object of this invention to provide means to controllably release safety locking mechanism for safely lowering the hoisting cable and for safely hoisting a load.

It is another object of this invention to provide a novel combination of friction clutch and brake adapted to a hoist with safety control mechanism.

It is another object of this invention to provide a crank controlled brake and clutch adapted to a safety hoist.

It is a prime object of this invention to provide in a winch a gear ratio accommodating hand operation and also therewith a power connection to the winch so that either hand or power operation may be utilized interchangeably.

It is a further object of this invention to provide in a winch a gear ratio accommodating hand operation and also therewith a power connection to the hand operated crank shaft of

approximately the same torque as is provided by hand whereby to utilize the minimum size of power source.

Other objects of this invention will be apparent from the description and drawings.

The U-shaped horizontally positioned frame 1 has a depending stub-shaft 2 revolvably fitting into the top of a telescopic mast 3 so that the frame may be pivoted about the stub shaft on the mast. The ends of the U-arms of the frame are provided with bearings 4 and 5 which support a shaft 6. The horizontal shaft 6 revolvably supports a winding drum 7 between the bearings 4 and 5 and a pair of links 8 and 9 outside of the bearings, pins 10 and 11 and washers 12 and 13 respectively holding the links in position. The links have eyes at their free ends adapted to support auxiliary equipment in the operating and stored positions of the apparatus, the auxiliary equipment not being shown. The drum 7 carries a cable 14 from

which depends a weight 15 and a hook 16, the weight and hook unwinding the cable by gravity under certain operating conditions later to be described. To the winding drum 7 is operatively connected a gear 17 in mesh with a pinion 18 freely mounted on a horizontal shaft 19 carried in bearings 20 and 21 on the U-frame between the drum 7 and the stub mast 2. The pinion 18 has a bell extension 22 which interiorly has a radially resisting pressure surface 23 and exteriorly a radially resisting pressure surface 24. The interior surface 23 of the bell co-acts with a fiber member 25 mounted on a cone 26 within the bell. On the cone 26 bolts 27 and 28 support brake shoes 29 and 30 with fiber linings 31 and 32 respectively held in place by shoulders 33 and 34 respectively. On the bolts 27 and 28 are compression springs 35 and 36 respectively which yieldingly support the respective brake shoes.

The cone 26 slides on the pinion shaft 19 and is operated thereon by compression spring 37 which is sufficiently powerful to engage the cone 26 and the brake shoes 29 and 30 with the bell 22 to their full operating capacity. The brake shoes 29 and 30 adjacent their supporting bolts 27 and 28 have spaces extending to cone 26 deep enough to accommodate withdrawal of the cone 26 from engagement with the bell 22 while the springs 35 and 36 maintain the brake shoes 29 and 30 in full engagement with the bell 22. Further withdrawal of the cone 26 by direct contact with the brake shoes 29 and 30 progressively withdraws them from the bell 22 whereby the braking effect of the shoes is lessened. The spring 37 transmits its thrust to the pinion shaft 19 by direct thrust on a collar 38 and pins 39 and 40 and by indirect thrust through the cone 26, and bell 22, the pinion 18 and the collar 41 with pin 42 in the shaft 19, the collar 41 and pin 42 being between the pinion 18 and the bearing 21. It is thus obvious that the cone 26 wedged in the bell 22 is self-retaining because of the wedge action between the nested elements 26 and 22 and subject to remote control by the driving crank for the supporting shaft 19.

The cone 26 is moved against the compression spring 37 by cross bar 43 extending transversely through an opening 44 in the shaft 19. The pin 43 acts also as a key and is supplemented by key 43''. Through an axial passageway in the shaft 19 terminating with the opening 44 before mentioned, a bar 45 extends to the pin 43 into which it is threaded. Outside of the frame 1 and adjacent the bearing 20 a cylindrically recessed collar 46 with a back piece 47 fits over the shaft 19 and is fastened by dowels 48 and 49 to the frame 1. Into the recessed collar 46 fits an inner collar 50 from which an enlarged collar 50' projects with horizontal ratchet like jaws 51. The inner collar 50 is held by a key 52 to shaft 19 for rotation therewith. The inner collar 50 is recessed horizontally to provide cages for rollers 53 and 54 with roll supporting surfaces 55 and 56 respectively. The roll supporting surfaces 55 and 56 provide runways on which the rollers 53 and 54 travel. The inner collar 50 is further recessed circumferentially to provide pockets for springs 57 and 58 which respectively operate on rolls 53 and 54 to force them along the respective supporting surfaces 55 and 56 to contact the inner ring like surface 59 of the cylindrically recessed collar 46.

Co-operating with ratchet like jaws 51 are ratchet like jaws 60 extending horizontally from

collar 61 held by dowels 62 and 63 on hub 64 of crank arm 65, the hub 64 being mounted for rotation on an overhung portion of the shaft 19. The collar 61 is recessed into the hub 64 of the crank. The hub 64 is held slidably on shaft 19 by a slip ring 66 through which extends rod 45 having locked nuts 67 on the outer end thereof.

The ratchet like jaws 51 and 60 have squared faces 51' and 60' which act squarely against each other to transmit the force from the crank to the shaft 19. They also have inclined surfaces 51'' and 60'' which slide against each other as shown in Figure 2 to transmit the force from the crank to the cone 26 when the crank is moved in a direction reverse to that required for hoisting. The sectional view in Figure 6 shows the jaws 51 and 60 in engagement.

Referring to Figures 7 to 10 inclusive, a modification of the invention is shown wherein the crank arm 65 is provided with handle 70 with connecting member 71 and with positive connection to the pinion shaft 19. Adjacent the handle 70 a lug 72 supports a rod 73 terminating adjacent the handle in a cross member 74 adapted to actuation by the thumb or finger of the hand engaging the handle 70. The rod 73 carries a collar 75 held by pin 76. Between the collar 75 and the lug 72 a spring 77 presses the rod 73 into the hub 64 and therethrough into a recess 78 in the shaft 19.

A number of recesses 78 circumferentially of the shaft 19 permit various driving positionings of the crank hub on the shaft. It will be noted that the key 52 is omitted from this embodiment of the invention and a substitute 52' therefor is provided on an overhung portion of shaft 19' adjacent bearing 21, also that a central longitudinal passage in shaft 19 is provided for a rod 79 on one end of which slip ring 66' and lock nuts 67' function to maintain the hub 64 on the shaft 19. On the opposite end of the rod 79 locknuts 80 bear against a rocking washer 81 seated in a pivoted arm 82 pressing the latter against a spring 83 bearing against slip rings 84 abutting on the end of the shaft portion 19'. The arm 82 is pivoted by bolt 85 through lug 86 extending laterally from the frame 1. The free end of the arm 82 carries a pair of wedge shaped projections 87 which have parallel faces fitting over a lug 88 extending laterally from the frame 1. Through the lug 88 passes a bolt 89 which carries a spring 90 and washer 91 between which brake rim extensions 92 and 93 of brake rims 94 and 95 respectively are pressed against the beveled faces of wedge shaped projections 87. The brake rims 94 and 95 are hinged on pin 96 in frame 1. Brake linings 97 and 98 respectively of rims 94 and 95 contact a brake ring 99 mounted on shaft extension 19'. The brake ring 99 is recessed to provide a thin back section 100 and to receive a disc 101 with a thin back section 102. The disc 101 is recessed horizontally on its circumference to retain rolls 103 and 104 on roll supporting surfaces 105 and 106 respectively. The roll supporting surfaces 105 and 106 provide runways on which the rolls travel. The disc 101 is further recessed circumferentially to provide pockets for springs 107 and 108 which respectively operate on rolls 103 and 104 to force them along the respective supporting surfaces 105 and 106 to contact the inner ringlike surface 109 of the cylindrically recessed disc 101. The disc 101 is held in fixed relationship to shaft 19' by key 52'. Also the pinion 18 is held in fixed relationship to shaft 19 by key 52''.

Referring to the preferred embodiment of the invention illustrated in Figures 11 and 12, the pinion gear 18' is shown rotatably supported on a sleeve 110 on a reduced section 19'' of shaft 19. The sleeve bears against a collar 111 adjacent a shoulder 112 of the shaft 19. Pin 42 in collar 41 passes through the sleeve 110 and maintains it in position. It is thus seen that the pinion gear 18' is restrained against longitudinal movement on the shaft 19-19''. The pinion 18' is provided with a bell extension 22' which interiorly has a radially resisting pressure surface 23'. The interior surface 23' is of a longitudinal length adapted to coact with a cone 26' and with a separate brake band 31' carried on a brake ring 112. The brake ring 112 is slidably mounted on hub 26'' of cone 26' and a key 113 prevents relative rotary movement between the ring and hub. Bolts 114 limit the sliding movement of the ring 112 away from the cone 26'. A space is provided between the cone 26' and the ring 112 such that the cone 26' may be completely disengaged from the bell 22' while allowing the brake band 31' to remain fully engaged with surface 23' of the bell 22'. Longitudinal movement of the cone 26' is controlled by the pin 43' extending transversely in an opening 44' in shaft 19, the shaft 19 having an axial passage through which a rod 45' extends from pin 43' to nuts 67''. The nuts 67'' bear against the hub 64 of crank 65 which operates on the shaft 19 as previously described in connection with Figures 1 to 6 inclusive. Spring 37' is of a strength sufficient to normally retain the cone 26' and the brake band 31' fully in engagement with surface 23' of the bell 22' by bearing on the hub 26'' at one spring end and on the collar 38 pinned to shaft 19 at the other spring end. The transverse opening 44' in the shaft 19 is of a length suitable to accommodate the travel of cross bar 43' necessary for the proper positioning of cone 26' and brake ring 112.

Referring to Figures 13 and 14, a hand winch frame 1 supports a motor 123 with reducing gear 124. The reducing gear 124 carries a coupling plate 122 facing independent coupling plate 121 fastened by means not shown to crank shaft 19' extending from the frame 1. A radial key 125 between coupling plates 121 and 122 is utilized to transmit the power of the reducing gear to the shaft 19' and 19. The hand winch is fully illustrated and described in connection with Figure 11. The frame 1 supports a controller 126 having a connection to a source of electricity and to the motor, neither of which connections is shown. The controller 126 has an operating arm 127 positioned to be operatively connected to the crank arm 65. From the crank arm 65 a pivoted link 128 with pin 129 extends to snap yoke 130 on the end of the controller operating arm 127. The snap yoke 130 facilitates the ready separation of link 128 and controller arm 127 while accommodating a hinge action between these members when they are in engagement.

The reducing gear 124 preferably includes a worm on the motor shaft and a worm gear connected to the shaft 19 with coupling plates 121 and 122. As thus constituted, the reducing gear acts as a self-locking device on the coupling plate 122 and on the following train of mechanism when the radial key 125 is in position. Magnetic braking apparatus 124' constitutes a part of the motor-reducing gear combination.

Referring to Figures 15 and 16, I provide inner collar 59 fastened by key 52 to shaft 19 but independent of enlarged collar 50'. Enlarged collar 75

50" is provided with horizontal ratchet like jaws 51" and with a radial screw fastening 52' to shaft 19. Radial fastening screw 52' is accessible readily from the exterior of the mechanism so that the operator may withdraw it whenever it is desirable to do so. Such withdrawal is desirable when power operation only is contemplated. When power operation is utilized, withdrawal of radial screw 52' releases the engaging jaws 51" and 60 and handle 65 from connection to the shaft 19 so that when the pivoted link 128 and snap yoke 130 engaging the controller arm 127 are put in motion by the handle 65 the controller 126 for the motor is readily manipulated to be in accord with operating requirements. When the radial screw 52' is withdrawn from shaft 19, key 52 still functions to hold inner collar 50 to its original function previously described. When hand operation of the hoist is utilized the radial screw 52' is adjusted inwardly to engage shaft 19 so that inner collar 50 and enlarged collar 50" act as a unit as set forth in the description in connection with Figure 11. The provision of radial screw 52' and the separation of collar 50" from collar 50 gives the necessary freedom of movement for handle 65 to function as a control medium for the motor. A lug 46' on the stationary collar 46 is so positioned that radial screw 52' only when withdrawn from shaft 19 will contact the lug to hold collar 50" and jaws 51" against further movement in direction of the lug. It is intended that the motor will be stopped by the controller by the time the screw 52' has made contact with the lug 46', and that further movement of the handle 65 while maintaining screw 52' in contact with lug 46' will be utilized to control the clutch to effect gravity lowering previously mentioned. A catch on the lug 46', not shown, or a second lug 46" may be utilized to hold the radial screw 52' so that the clutch may be again engaged after the manner previously described in connection with Figure 11. By releasing the handle 65 the clutch spring 37 will be allowed to force the jaw 60 forward along jaw 51" to the limit of its travel and thus engage the clutch.

Operation

The operation of the embodiment of the invention shown in Figures 3 to 6 inclusive will now be considered. Assuming that the cable 14 is lowered and that a load is positioned thereon for hoisting, the crank 65 is then turned in a forward direction. The jaws 60 of the crank hub 64 contact the interfitting jaws 51 of the disc 50 which through key 52 transmits motion to the shaft 19. The shaft 19 through key 43" transmits motion to the clutch cone 26. Clutch cone 26 is continuously under pressure of spring 37 and in the absence of restraining force the clutch is in constant engagement via band 25 with clutch bell 22 on pinion gear 18 so that motion of the crank 65 is carried through pinion 18 to the hoisting gear 11, drum 7 and cable 14. Upon completion of the hoisting operation, force to turn the crank is relieved and immediately the tendency to reverse operation due to the suspended load is checked by the rollers 53 and 54 in disc 50 becoming operative through the slightest reverse movement of disc 50 upon the inclined supporting surfaces 55 and 56 on the one side and upon the ringlike surface 59 on the other side. The rolls wedge between the respective surfaces and provide an efficient silent holding means against reverse operation of the chain of elements described. Now assuming that a load

is to be lowered from the last mentioned position of the members. Force is applied to the crank to move it in the reverse direction. The temporarily stationary inclined faces 51" of disc 50 in contact with inclined faces 60" on the hub 64 become operative to force the hub 64 in its backward travel to move longitudinally of shaft 19 and to effect through slip ring 66, nuts 67, rod 45, and cross pin 43 a retraction of cone 26 against spring 37 and from bell 22 in a selective manner. The greater the backward travel the greater the retraction. Upon complete release of the cone 26 from the bell 22 the cone 26 contacts the brake shoes 29 and 30 thereby placing the control of the brake shoes with crank 65, and further retraction of the cone 26 selectively withdraws the brake shoes off the outside of the bell 22. The degree of withdrawal of the brake shoes is regulated in accordance with the operator's observation of the speed of the descending load. Upon completion of the lowering operation the backward force on the crank 65 is relieved by removal of backward pressure by the operator on the crank 65, the spring 37 extends itself thereby moving the cone 26 towards the bell 22 thereby increasing the brake shoes 29 and 30 contact exteriorly of the bell to a degree that allows the cone 26 to engage the interior of the bell. The expansive force of the spring 37 is also exerted through key 43, rod 45, nuts 67 and slip ring 66 upon hub 64 and upon the inclined faces 51" and 60". These faces 51" and 60" are of a degree of inclination and relative smoothness to promote the ready return of the hub under the force of spring 37 to a holding position with ratchet jaw faces 51' and 60' in contact.

Referring to the operation of the embodiment of the invention shown in Figures 7 to 10 inclusive, again assume that the cable 14 is lowered and that a load is positioned thereon for hoisting, also that the rod 73 is seated in one of the recesses 78 on the shaft 19. Forward motion of the crank through pin 73, shaft 19, key 52", pinion 18 and gear 17 is transmitted to a hoisting movement of the cable 14. If the operator's hand is removed from handle 70 the backward tendency to movement due to the suspended load is met by restraint through key 52", disc 101, the inclined faces 105 and 106 supporting lock rollers 103 and 104 against surface 109 of brake ring 99, and brake bands 94 and 95 supported on pin 96 in frame 1. The brake rims or bands 94 and 95 are normally held on brake ring 99 by force of spring 90.

Now assuming that a load is to be lowered from the last mentioned position, the operator grasps the handle 70, moves rod 73 radially until it is free from recess 78 and then moves the crank 65 in a backward direction. Contact of faces 51" of disc 50 with inclined faces 60" on hub 64 become operative in its backward travel to force the hub 64 to move longitudinally of shaft 19 in consequence of rollers 53 and 54 locking disc 50 and jaws 51 from backward movement as before described. Longitudinal movement of hub 64 through slipring 66, locknuts 67', rod 79, locknuts 80, accommodation washer 81, pivoted arm 82, and wedges 87 acts upon brake rim extensions 92 and 93 to separate brake rims 94 and 95 selectively against spring 90 thereby permitting rotation of brake ring 99 and the shaft 19 (in the reverse direction), gear train and cable drum and the lowering of the hook 16. The rate of lowering is regulated by the degree of brake rim separation in turn dependent upon backward travel

of the crank 65. Spring 83 is continuously active against pivoted arm 82 and its force through rod 79 and associated attaching elements extends to hub 64 sufficiently to force the hub 64 to a forward movement position while arm 82 removes the wedge members 87 from brake rim extensions 92 and 93 sufficiently to let the brake rims 94 and 95 operate to hold brake ring 99.

Referring to the operation of the embodiment 10 of the invention shown in Figures 11 and 12, again assume that the cable 14 is lowered and that a load is positioned thereon for hoisting, also that the crank 65 is then turned in a forward direction. The jaws 60 of the crank hub 64 contact the interfitting jaws 51 of the disc 50 which through key 52 transmits motion to the shaft 19. The shaft 19 through key 43' transmits motion to the clutch cone 26'. Clutch cone 26' is continuously under pressure of spring 37' and in the absence of restraining force the clutch is in constant engagement via metal to metal contact with clutch bell 22' on pinion gear 18' so that motion of the crank 65 is carried through pinion 18' to the hoisting gear 17, drum 1 and cable 14. Upon completion of the hoisting operation, force to turn the crank is removed and immediately the tendency to reverse operation is checked by the rollers 53 and 54 as previously described. Now assuming that a load is to be lowered from the last mentioned position of the members. Force is applied to the crank to move it in the reverse direction. The temporarily stationary inclined faces 51" of disc 50 in contact with inclined faces 60" on the hub 64 become operative to force the hub 64 in its backward travel to move longitudinally of shaft 19 and to effect through slipring 66, nuts 67", rod 45' and cross pin 43' a retraction of cone 26' against spring 37' and from bell 22' in a selective manner. The greater the backward travel of the crank 65 the greater the retraction of the cone 26'. Upon complete release of the cone 26' from the bell 22' the cone 26' contacts the brake ring 112 thereby placing control of the brake ring with the crank 65, and further retraction of the cone 26' selectively withdraws the brake ring 112 and its lining 31' from the inside of the bell 22'. The degree of withdrawal of the brake ring is regulated in accordance with the operator's observation of the speed of the descending load. Upon completion of the lowering operation the backward force on the crank is removed by removal of backward pressure by the operator, whereupon the spring 37' extends itself thereby moving the cone 26' towards the bell 22' thereby increasing the contact of brake lining 31' with bell 22' and the travel of the ring 112 within the bell until the cone 26' fully engages the bell 22'. The expansive force of the spring 37' is also exerted as previously described to return the hub 64 to a hoisting position.

The relation of the metal cone 26', the slip ring 112 and brake band 31' to the pressure surface 23' of bell 22' is a particular one new to the art. The metal surface 23' is tapered and the metal cone 26' fits the surface 23', their degree of angularity being such that a slight movement of the cone 26' axially attains prompt complete disengagement or engagement. The brake band 31' is of a compressible friction producing material 65 which expands or contracts radially as the slip ring 112 is moved axially of the cone or bell. The expansive force of the braking material is utilized during the axial movement of the ring 112 to maintain contact with the surface 23', although at a changing degree of pressure in consequence 70 75

of the change in radial restraint by the tapered surface 23'. The axial length of the surface 23', the axial length of the cone 26', the axial length of the brake band 31' and the thickness of the latter are selected to give, along with the degree of cone and band angularity, quick in and out action of the cone, continued braking effect of varying degree by the braking band 31', and reliability of action of either clutch or brake individually.

The operation of the embodiment of the invention disclosed in Figures 13 and 14 is controlled by keys 125 and 52 and by the controller 126. With the snap yoke 130 disengaged and radial key 125 removed, the mechanism operates as set forth in connection with Figures 11 and 12, key 52 functioning to transmit the crank effort to the shaft 19. With the snap yoke 130 engaged and radial key 125 in place, it is desirable to disengage key 52 so that the crank 65 may be utilized to control the motor 123 and the clutch cone 26'. While the key 52 is apparently inaccessible, the members to the right thereof as shown in Figure 11 are readily removable. However, a radial key 52' in the form of a screw through member 51 into shaft 19, though not fully illustrated is contemplated to give accessibility from the exterior of the apparatus and so almost instantaneous selectivity of mode of operation. The key 52 or radial screw 52' being disengaged, the self locking reducing gear 124 is utilized to hold the mechanism. Backward movement of the crank 65 pushes the control lever 127 down to stop the motor, initiate magnetic braking and to lock the hoisting drum. Further backward movement of the crank 65 gradually disengages cone 26' from bell 22' of the clutch in consequence of the crank movement along shaft 19 and allows the operation of the drum 7 by gravity. Forward movement of the crank will instantly be initiated by spring 37 upon manual release of the crank 65 until the clutch is engaged and the mechanism is locked. Further movement of the crank is utilized to operate the controller to initiate motor operation. Obviously the controller may be operatively connected with the crank 65 in a variety of ways. The controller 126 can also be connected to the motor 123 to operate independently of the crank 65 like push button control and the crank 65 then can be utilized for lowering. The positioning of the controller so that it may be operatively connected with the crank extends the selectivity of modes of operation of the mechanism. With the snap yoke 130 disengaged, the controller arm 127 is available for direct manual manipulation and such action is contemplated; the crank arm 65 being held by spring 37 and rotating with shaft 19 as propelled by the motor 123. The various modes of operation available will be utilized selectively to meet the peculiar situations incident to individual installations.

The type of holding mechanism herein set forth is practically instantaneous and silent in its operation necessary to hold the pinion shaft 19. It eliminates the noise and clatter incident to the use of the pawl and ratchet holding device. It also eliminates the silencer usually provided for the pawl and ratchet.

A number of variations of the embodiments of the invention disclosed are contemplated to fall within the scope of the appended claims. For example, referring to Figure 11, the portion of the pinion shaft 19' within the pinion and its bell may be divided from the shaft 19. In this case the pinion supporting portion 19'

may be variously utilized, in one instance keyed to and rotatable with the pinion and recessed to support the shaft 19, in another instance the portion 19" may be joined to the frame as a stud and recessed to support the shaft 19. In Figure 4, surfaces 55 and 56 shown straight may be curved circularly with a decreasing curve slope opposite the spring end to provide a proper incline for engaging the roller 53 between surfaces 55 and 59 and 56 and 59. While these instances of variation are not fully illustrated, they are set forth as valued additions to the art, and their action is readily apparent from the reference given.

I claim:

1. In a hoisting winch, having a frame, a hoisting drum rotatably mounted on said frame, a gear operatively connected to said drum, a pinion gear in engagement with said first mentioned gear, a mounting for said pinion gear comprising a cored driving shaft fixed longitudinally relative to said pinion gear and rotatably supported on said frame, a releasable driving connection between said pinion and said driving shaft, means to hold said shaft from backward rotation, a crank mounted on an overhung portion of said shaft, the combination of, a releasable connection between said crank and said overhung shaft portion transmitting to the latter and said pinion forward motion of said crank and allowing backward motion of said crank, and means mounted in said cored driving shaft actuated by said crank in its backward motion controlling said first mentioned pinion driving connection and therewith the backward movement of said pinion whereby the lowering motion of said hoisting drum is regulated.
2. In a hoisting winch, the combination comprising a frame, a hoisting drum rotatably mounted on said frame, a gear operatively connected to said drum to rotate therewith, a pinion gear in engagement with said first mentioned gear, a mounting for said pinion gear comprising a cored shaft fixed longitudinally relative to said pinion gear and rotatably supported on said frame, means to hold said shaft from backward rotation, a longitudinally movable crank mounted on an overhung portion of said shaft, a connection between said crank and said overhung shaft portion transmitting to the latter forward motion of said crank and allowing backward movement of said crank, releasable means normally holding said pinion in driving connection with said pinion mounting shaft, and means mounted in said cored shaft actuated by said crank in its backward motion releasing said releasable means between said pinion gear and its mounting shaft.
3. In a hoisting winch, the combination comprising a frame, a hoisting drum rotatably mounted on said frame, a gear operatively connected to said drum, a freely rotatable pinion gear in engagement with said first mentioned gear, a mounting for said pinion gear comprising a cored shaft fixed longitudinally relative to said pinion gear and rotatably supported on said frame, means to hold said shaft from backward rotation, a crank mounted on an overhung portion of said shaft, a connection between said crank and said overhung shaft portion transmitting to the latter forward motion of said crank and allowing backward movement of said crank, releasable means normally holding said pinion in driving connection with said pinion mounting shaft, and means mounted in said

cored shaft actuated by said crank in its backward motion releasing said releasable means between said pinion gear and said shaft.

4. In a hoisting winch, the combination comprising a frame, a hoisting drum rotatably mounted on said frame, a gear operatively connected to said drum, a freely rotatable pinion gear in engagement with said first mentioned gear, a mounting for said pinion gear comprising a cored shaft fixed longitudinally relative to said pinion gear and rotatably supported on said frame, means to hold said shaft from backward rotation, a crank mounted on an overhung portion of said shaft, a connection between said crank and said overhung shaft portion transmitting to the latter forward motion of said crank and allowing backward movement of said crank, releasable means normally holding said pinion in driving connection with said pinion mounting shaft and means mounted in said cored shaft actuated by said crank in its backward motion progressively releasing said releasable means between said pinion gear and said shaft thereby controlling the free rotation of said pinion gear.

5. In a hoisting winch, the combination comprising a frame, a hoisting drum rotatably mounted on said frame, a gear operatively connected to said drum, a freely rotatable pinion gear in engagement with said gear, a mounting for said pinion gear comprising a cored shaft fixed longitudinally relative to said pinion gear and rotatably supported on said frame, means to hold said shaft from backward rotation, a crank mounted on an overhung shaft portion transmitting to the latter forward motion of said crank, a friction clutch normally holding said pinion in driving connection with said shaft, and means mounted in said cored shaft actuated by said crank in its backward motion releasing said friction clutch.

6. In hoisting apparatus, a frame, a winding drum mounted on said frame, a gear operatively connected to said drum, a pinion gear in driving engagement with said first named gear, a shaft crosswise of said frame fixed longitudinally relative to and coaxial with said pinion gear, means for preventing rotation of said shaft in one direction; a drive connection between said pinion gear and said shaft having a member movable axially of said shaft adapted to engage or disengage said connection, a second cross member manually operated to control said axially movable member, a drive connection to said cross shaft and a manual member rotatable about and movable along the axis of said shaft and adapted to actuate said second cross member.

7. In hoisting apparatus, a frame, a winding drum mounted on said frame, a gear operatively connected to said drum, a pinion gear in driving engagement with said first named gear, a shaft crosswise of said frame coaxial with and fixed longitudinally relative to said pinion gear, means including a pair of nested friction elements coaxial with said shaft for revolving said pinion gear with said shaft in one direction to rotate said drum, means for preventing the rotation of said shaft oppositely to the said one direction, and means for disengaging said pinion gear so that it can rotate freely, said disengaging means including a manual driving member for said shaft and a second crosswise member for separating said nested friction elements from their self retaining wedged relationship.

8. In a hoisting apparatus, a frame mounted on a telescopic mast, a winding drum mounted on said frame, a gear fixed to said drum, a pinion gear in driving engagement with said first named gear, a shaft crosswise of said frame and coaxial with and fixed longitudinally relative to said pinion gear, a manual crank mounted for longitudinal movement on said shaft, a self engaging friction clutch including a pair of nested friction elements joining said pinion gear and said coaxial shaft, pressure means adapted to engage said clutch, means for disengaging said clutch and for rotating said clutch comprising a second crosswise member operatively connected to said clutch and to said crank, and means for preventing backward rotation of said coaxial shaft and said pinion effective on said pinion by wedge action between said nested friction elements.

9. In hoisting apparatus a frame, a winding drum mounted on said frame, a gear operatively connected to said drum, a pinion gear in driving engagement with said first named gear, a cross shaft coaxial with said pinion gear, a friction clutch including nested friction elements between said pinion gear and said shaft, means normally maintaining said clutch in engagement, means for revolving said shaft in one direction including a manual driving member, a second cross member adapted for separating said friction elements by connection with said manual member, and means for preventing the rotation of said shaft in the opposite direction, wedge action between said nested friction elements of said clutch being regulated by said second cross member.

10. In a winch having a frame, a hoisting drum rotatably mounted on said frame, a gear operatively connected to said drum, a pinion gear in engagement with said first named gear, and mounted for rotation on said frame a cored drive shaft supporting said pinion and with a drive connection therebetween, and means to hold said pinion from rotation in one direction; the combination comprising a crank mounted for longitudinal movement on an overhung portion of said drive shaft, a spindle mounted for axial movement in said cored shaft and adapted to control said pinion holding means, pressure means controlling axial movement in one direction of said spindle, an operative connection between said crank and said spindle giving to the latter axial movement opposite to said one direction thereby releasing said pinion for rotation.

11. In a winch having a frame, a hoisting drum rotatably mounted on said frame, a gear operatively connected to said drum, a pinion gear in engagement with said first named gear, and mounted for rotation on said frame a cored drive shaft supporting said pinion and with a drive connection therebetween, and means to hold said pinion from rotation in one direction; the combination comprising a crank mounted for longitudinal movement on an overhung portion of said drive shaft, a spindle mounted for axial movement in said cored shaft, a clutch connection between said shaft and said pinion, a control connection between said spindle and said clutch, and an operative connection between said spindle and said crank whereby the movement of said crank regulates the position of said control connection and thereby said clutch.
